UNITED STATES PATENT OFFICE

PAUL F. WOODRUFF, OF FAIRPORT HARBOR, OHIO

FREE ARCH SHOE

Application filed June 15, 1929. Serial No. 371,127.

This invention relates to what may be termed a free arch shoe, that is one in which the arch portion or instep of the wearer's foot is not bound tightly to the sole of the shoe. The shoe of the present invention contains no arch support in the sense of a stiff member to which the arch of the foot is continuously connected. On the contrary, the arch is left free to assume its natural position and to move freely during walking.

The lacing of shoes, as shoes have been constructed heretofore, has had a tendency to draw the arch of the wearer's foot toward and onto the relatively stiff unyielding shoe sole, as represented diagrammatically in Fig. 6, thereby causing discomfort and tending to break down the arch of the foot. Not only in standing and walking but in sitting as well, there is an initial stress upon the arch 20 of the foot where the latter is tightly bound to the sole of the shoe with lacing, buttons or other fastening devices, and this stress is momentarily increased during each step taken. Usually the shank of the sole is made quite narrow, and sometimes it is made relatively thin, with a view to the prevention of such stresses. The shank of the sole cannot be dispensed with entirely, however, because the foot must be protected from injury from 30 below, and because the heel and the forward portion of the sole must be tied together and a bearing must be provided for all portions of the foot which transmit load to the earth. So long as any sole whatever remains in the 35 mid portion of the shoe, it will be stiffer than the rest of the shoe surrounding the arch portion of the foot. In walking, the contour of the foot changes constantly. On account of the stiffness necessarily present in shoe soles, it is impossible to construct them so as to follow the continuously changing contour of the foot in walking.

The present invention has to do with the provision of means for enclosing the arch or instep of the foot without restricting freedom of movement and without departing from the use of the conventional shoe sole. I prefer to accomplish this result by causing 40 the instep portion of the shoe upper to extend beneath the arch of the foot as well as

along the sides and over the top thereof, and to leave this portion of the upper entirely detached from the shoe sole. With a shoe constructed in this manner, the lacing of the shoe across the arch of the foot exerts pressure inwardly upon the foot in all directions, and not merely downwardly, and hence there is no tendency to force the foot downwardly and break the arch. The appearance of such a shoe need not be noticeably different from that of the present conventional type.

One object of the invention is the provision of a free arch shoe, that is one in which the freedom of movement of the wearer's 55 arch is not interfered with.

Another object is the provision of a shoe, as above defined, in which the under side of the foot is protected from injury throughout its length.

Other objects and features of novelty will appear as I proceed with the description of that embodiment of the invention which, for the purposes of the present application, I have illustrated in the accompanying drawings, in which:

Fig. 1 is a perspective view of a shoe embodying the invention;

Fig. 2 is a horizontal sectional view taken substantially on the line 2—2 of Fig. 1, or on 80 the line 2—2 of Fig. 3;

Fig. 3 is a vertical longitudinal sectional view of the same;

Fig. 4 is a cross sectional view taken substantially on the line 4—4 of Fig. 1, or on 85 the line 4—4 of Fig. 2;

Fig. 5 is a view similar to Fig. 4, showing a modification of the invention; and

Figs. 6 and 7 are diagrammatic views depicting the effect of forcing the instep of the 90 foot down tightly upon an unyielding support like the stiff sole of a shoe.

The shoe illustrated in the drawings has a sole comprising a forward portion 10, a shank 11 and a heel 12 of heavy stiff leather. The counter of the shoe is shown at 13, the shoe illustrated being a low cut shoe, although, obviously, it could as well be a high one. The toe portion of the upper is shown at 14 and the vamp at 15. 16 and 17 are in- 105

soles. There is no insole for the mid portion of the shoe for the reason that an insole there would interfere, to some extent, with the pliability of the shoe upper at this point.

5 The securing of the upper to the sole may be accomplished in the conventional manner in so far as the forward portion of the shoe and the heel portion are concerned. The welt is indicated at 18. In the conventional 10 shoe the welt ordinarily extends all around the toe and along the sides of the shoe back at least as far as the heel. In the present instance, however, it extends back along the 15 sides of the shoe only to a position just forward of the arch portion, and then extends across the shoe, as indicated in Fig. 2. The welt may be attached to the toe portion 14 of the upper by stitching 19, indicated in Figs. 2 and 3, and to the sole 10 by further stitching 20. The vamp 15 has a continuous lower portion 21 extending transversely and arched, as indicated in Fig. 3, to fit more or less snugly the foot of the wearer. It is stitched to the counter 13 and the toe portion 14 of the upper in the usual or any desirable way. At its forward end the transverse portion 21 of the vamp is sewed to the transverse portion of the welt 18 by a line of stitching 22. At its rear end it is secured to the heel 12 along a transverse line indicated at 23. The counter 13 is divided across the instep and provided with eyelets for lacing. 24 represents the usual shoe tongue.

When the shoe is laced up upon the foot 35 of the wearer the transverse part 21 of the vamp is drawn up snugly against the lower part of the wearer's instep. At times, particularly in standing and walking, there will be more or less contact between this part 21 and the shank 11 of the sole, Fig. 4 illustrating such a condition. At all times, however, there is perfect freedom of movement of that portion of the upper between the points or lines 22 and 23, and consequently the arch or 40 instep of the wearer is free to take the varying positions which it naturally assumes in walking, standing or sitting.

The term "lacing", as used hereinafter, is intended to include buttoning and any other 50 form of fastening capable of exerting pressure upon the foot.

While the most desirable means known to me for carrying the invention into effect is that above described, it is possible to employ other and more or less different constructions, as for instance, that illustrated in Fig. 5, where the vamp portion of the shoe is shown attached to the shank 11 of the sole along each side, the vamp in this case, however, comprising a leather portion 35 and an extensible portion 36 formed of rubber or the like. When a shoe of this construction is laced up, the portion 36 stretches, and hence no pressure, tending to break down the arch, 60 is exerted.

In Figs. 6 and 7, 30 represents a stiff flat support corresponding to the sole of a shoe, and 31 is a bolt which may represent in its action the effect of lacing a shoe. A foot with a normal arch is shown in Fig. 6, the nut 70 32 on the bolt 31 not being screwed down. In Fig. 7 the nut 32 is shown screwed down as far as it will go, clamping the foot tightly against the support 30, thereby breaking the arch of the foot in much the same manner as occurs when the ordinary shoe is laced tightly.

While in foregoing description and accompanying drawings I have illustrated more or less in detail a preferred embodiment of the invention, I desire it to be understood that such detailed disclosure is primarily for the purpose of fully illustrating the invention, and is not to be construed as amounting to a limitation upon the scope thereof.

Having thus described my invention, I claim:

1. In a shoe, a sole having a relatively stiff shank, and an upper comprising a middle uniform ply portion adapted to entirely surround the arch of the wearer's foot, said middle portion being attached to the sole at the forward and rear ends only of the arch.

2. In a shoe, a sole having a relatively stiff shank, an upper formed to extend entirely around the foot of the wearer throughout the arch portion thereof, and means for attaching the upper to the sole at the heel and in front of the arch only, the remaining portion of the upper being formed of single ply material free of attachment to the sole.

3. In a shoe, a sole having a relatively stiff shank, and an upper extending continuously from heel to toe comprising a portion adapted to surround the instep of the wearer, said portion being of uniform pliability and free of attachment to said shank.

4. In a shoe, a sole having a relatively stiff shank, an upper attached to the sole around the forward portion of the shoe and along the sides and across the shoe directly behind the ball of the wearer's foot, said upper being further attached to the sole around the rear and sides of the heel and crosswise of the sole directly in front of the heel, the intermediate portions of the upper being free of attachment to the sole.

5. In a shoe, a sole having a relatively stiff shank, and an upper extending from heel to toe having an intermediate uniform ply portion adapted to surround the instep of the wearer, said portion being continuous with the forward and rear portions of the upper and free of attachment to said shank.

In testimony whereof, I hereunto affix my signature.

PAUL F. WOODRUFF.
